ARTIFICIAL HAND

Raymond B. Trautman, Minneapolis, Minn.

Application March 18, 1946, Serial No. 655,206

3 Claims. (Cl. 3—12)

1

My invention relates to improvements in artificial hands and particularly to that type of appliance disclosed in Letters Patent of the United States, No. 1,362,156, granted to me December 14, 1920, for Artificial hand.

It has been found in practice that the artificial hand, patented as aforesaid, is particularly advantageous in respect to the feature whereby the thumb is locked closed with its tip in engagement with the tips of fingers of the hand. Said patented hand, however, has been somewhat objectionable due to inadequate opening of the thumb which deprived the user from grasping relatively bulky objects and due, further, to the path followed by the thumb-tip in relation to the main portion of the hand whereby the user, when seated, was obliged unnaturally to present the hand, not flatwise but more nearly endwise to the horizontal surface of a desk, table or the like in order to grasp an object thereon.

Broadly, it is a purpose of my present invention to overcome the above noted objections to my original invention, without sacrificing its thumb-locking feature or any of its other advantages.

More particularly, it is an object of my present invention to provide an artificial hand of the character indicated in which the thumb, though releasably locked closed upon the fingers, may be opened exceptionally wide by mechanism fully accommodated within the hand proper and opened so that the tip of the thumb is caused to travel in a relatively flat arc generally paralleling the hand proper, whereby the wearer of the hand, seated at a desk, table or the like, can, in natural manner, present the hand substantially flatwise in respect to the horizontal surface thereof and swing the thumb under the hand readily to grasp an object resting on such surface.

Other objects of the invention reside in the novel combination and arrangement of parts and in the details of construction hereinafter illustrated and/or described.

In the drawings, Fig. 1 is a view illustrating an artificial hand from the back thereof, the same being an embodiment of the present invention and partially broken away to reveal otherwise concealed parts; Fig. 2 is a view of the appliance illustrated in Fig. 1 and showing the same from the thumb-side thereof with the thumb closed, said view being broken away to reveal parts within the hand proper for operating the thumb; Fig. 3 is a view similar to Fig. 2 showing the thumb in an open position.

2

Reference being had to the accompanying drawings, it will be seen that the artificial hand illustrated therein includes a main portion 10 with rigid fingers 11 thereon, the former having an elongated cavity 12 therein extending longitudinally thereof and opening at its palm-side. Two pintles 13, 14 mounted in the main portion 10 of the hand traverse the cavity 12 therein between the palm-side and the back thereof. The first or foremost pinte 13 substantially parallels the back of said main portion 10 adjacent thereto and to the butts of the fingers 11. The second or rearmost pinte 14 is spaced rearwardly from said first pinte 13.

Accommodated within the cavity 12 and swingably pivoted on the foremost pinte 13 is an arm 15 formed with a slot 16 therein extending lengthwise thereof. This arm 15 has a mounting branch 17 issuing sidewise therefrom and extending outwardly of the cavity 12. The mounting branch 17 is received within a kerf 18 formed in a thumb 19 and said thumb is riveted to said mounting branch.

The thumb 19 swings with the arm 15 from an open position substantially at right angles to the main portion 10 of the hand to a closed position wherein the thumb-tip engages the tips of the first and second fingers 11. Said thumb 19 has a reduced butt portion 20 which is received within the cavity 12 and said butt portion 20 has a rearward extension 21 which closes the cavity 12 rearwardly of the thumb proper in the closed and partially closed positions of said thumb.

A lever 22, swingably pivoted on the rearmost pinte 14, has a pin 23 issuing therefrom and slidably engaged in the slot 16 to provide a pin-and-slot connection between said lever 22 and arm 15. This pin-and slot connection causes said arm 15 to swing in response to the swinging of the lever 22 and, in the closed position of the thumb 19, said pin-and-slot connection further causes said arm 15 to be locked, in turn, to lock said thumb closed against forces applied thereto and tending to open the same.

A pull-cord 24 running through an opening 25 in the back of the main portion 10 of the hand and attached to the free end of the lever 22 swings said lever toward the back of said main portion 10 to open the thumb 19, such opening movement of the thumb being limited by engagement of the thumb extension 21 with the rearmost pinte 14. A tensioned spring 26, coiled about said pinte 14, is secured at one end thereof to the lever 22 and anchored at its other end to the hand proper, as at 27. This spring 26, while

yielding to the swinging of the lever 22 by the pull-cord 24, acts to reverse the throw of said lever and close the thumb 19 upon the slackening of said pull-cord.

In the cycle of movement of the thumb 19, the pin-and-slot connection between the arm 15 and lever 22 moves from a starting position adjacent the palm-side of the main portion 10 of the hand wherein the thumb is closed, then passes between the two pintles 13, 14 arriving at a position adjacent the back of said main portion 10 wherein the thumb is fully opened, and then retraces itself passing again between the pintles 13, 14. When said pin-and-slot connection passes between said pintles 13, 14, upon its throw in either direction, the movement of the pin 23 along the slot 16 will be reversed. This reversal of movement of said pin 23 within said slot 16 provides a relatively wide-opening swing of the thumb 19 through a relatively short arm and a relatively short lever, both conveniently accommodated within the confines of the main portion 10 of the hand. The pivoting of the thumb 19 at the location above described not only enables it to open relatively wide but causes its tip to travel in a relatively flat arc generally paralleling the hand proper. Thus, a user of the hand sitting before the horizontal working surface of a desk, table or the like can, readily and in natural manner, pick up objects from or place them upon such surface with the hand disposed substantially flatwise relative thereto. This feature obviously dispenses with any necessity of unnaturally disposing the hand substantially on end with respect to the work surface to enable the thumb-tip to move into closed position along such surface.

Changes in the specific form of my invention, as herein described, may be made within the scope of what is claimed without departing from the spirit of my invention.

Having described my invention, what I claim as new and desire to protect by Letters Patent is:

1. An artificial hand including a main portion and fingers thereon, the former having an elongated cavity therein extending longitudinally thereof and opening at its palm-side, a foremost pintle and a rearmost pintle in the main portion traversing the cavity therein between the palm-side and the back thereof, an arm swingably pivoted on said foremost pintle and formed with a slot therein extending lengthwise thereof, a mounting branch issuing sidewise from said arm outwardly of said cavity, a thumb member secured to said mounting branch and swingable therewith from an open position substantially at right angles to the main portion of the hand to a closed tip-to-tip position in relation to the fingers, a lever swingably pivoted on said rearmost pintle, a pin on the lever slidably engaged in the slot in said arm and providing therewith a pin-and-slot connection for swinging the arm in response to the swinging of said lever and for locking said arm in the closed position of the thumb, said connection being movable back and forth between the two pintles from a starting position adjacent the palm-side of said main portion wherein the thumb is locked closed to a position adjacent to the back of said main portion wherein the thumb is openly disposed, spring

means reacting against the lever for swinging the same in direction to close the thumb, a pull-cord attached to said lever for swinging the same in direction to open the thumb, said thumb having a rearward extension adapted to close the cavity rearwardly thereof in the closed position of said thumb, said extension being further adapted to engage said rearmost pintle to limit the opening throw of said thumb.

10. An artificial hand including a main portion and fingers thereon, the former having an elongated cavity therein extending longitudinally thereof and opening at its palm-side, a first pintle and a second pintle in the main portion traversing the cavity therein between the palm-side and the back thereof, an arm swingably pivoted on said first pintle and formed with a slot therein, a mounting branch issuing from said arm outwardly of said cavity, a thumb member secured to said mounting branch and swingable therewith from an open position substantially at right angles to the main portion of the hand to a closed tip-to-tip position in relation to the fingers, a lever swingably pivoted on said second pintle, a pin on the lever slidably engaged in the slot in said arm and providing therewith a pin-and-slot connection for swinging the arm in response to the swinging of said lever, said connection being movable back and forth between the two pintles crosswise through the plane common to the axes thereof from a starting position adjacent the palm-side of said main portion wherein the thumb is closed to a position adjacent to the back of said main portion wherein the thumb is openly disposed, spring means reacting against the lever for swinging the same in direction to close the thumb, a pull-cord attached to said lever for swinging the same in direction to open the thumb, and means for limiting the opening throw of said thumb.

30. An artificial hand including a main portion and fingers thereon, an arm and a lever both pivoted on said main portion and swingable on relatively spaced parallel pivotal axes, a pin-and-slot connection between said arm and lever, a thumb mounted on the arm and swingable therewith back and forth from a closed tip-to-tip position in relation to the fingers to an open position substantially at right angles to the main portion of the hand, means for swinging the lever to effect such thumb-swinging movement of said arm through said pin-and-slot connection, said connection releasably locking the thumb in its closed position and moving to and fro crosswise through the space between said pivotal axes upon each cycle of said arm and lever in opening and closing said thumb, the pin in said connection reversing its movement in the slot thereof upon the movement of said connection through said space in either direction.
